US00D881886S

(12) **United States Design Patent** (10) Patent No.: **US D881,886 S**
(45) Date of Patent: **** Apr. 21, 2020**

(54) **OPTICAL SCANNER**

(71) Applicant: **Hand Held Products, Inc.**, Fort Mill, SC (US)

(72) Inventors: **Dean J. Bidwell**, Renton, WA (US); **John S. Bandringa**, Everett, WA (US); **Roger Jackson**, Lake Forest Park, WA (US); **Tim Zurmoehle**, Seattle, WA (US); **William Herweh, III**, Seattle, WA (US); **Churu Yun**, Seattle, WA (US); **Matthew McElvogue**, Seattle, WA (US); **Rajat Shail**, Chicago, IL (US)

(73) Assignee: **HAND HELD PRODUCTS, INC.**, Fort Mill, SC (US)

(**) Term: **15 Years**

(21) Appl. No.: **29/695,762**

(22) Filed: **Jun. 21, 2019**

(57) **CLAIM**

We claim the ornamental design for an optical scanner, as shown and described.

DESCRIPTION

FIG. 1 is a top, front perspective view of an optical scanner showing our new design;

FIG. 2 is a bottom, front perspective view thereof;

FIG. 3 is a bottom, rear perspective view thereof;

FIG. 4 is a front elevation view thereof;

FIG. 5 is a rear elevation view thereof;

FIG. 6 is a right elevation view thereof;

FIG. 7 is a left elevation view thereof;

FIG. 8 is a top plan view thereof; and,

FIG. 9 is a bottom plan view thereof.

The broken lines shown herein are for illustrative purposes, represent unclaimed features, and form no part of the claimed design.
